(57) **CLAIM**

The ornamental design for a wireless receiver, as shown and described.

DESCRIPTION

FIG. 1 is a top perspective view of a wireless receiver showing my new design;

FIG. 2 is a bottom perspective view therof;

FIG. 3 is a front view thereof;

FIG. 4 is a rear view thereof;

FIG. 5 is a top plan view thereof;

FIG. 6 is a bottom view thereof;

FIG. 7 is a left side view thereof;

FIG. 8 is a right side view thereof;

FIG. 9 is a top perspective view with antennas removed;

FIG. 10 is a bottom perspective view with antennas removed;

FIG. 11 is a front view with antennas removed;

FIG. 12 is a rear view with antennas removed;

FIG. 13 is a top plan view with antennas removed;

FIG. 14 is a bottom view with antennas removed;

FIG. 15 is a left side view with antennas removed; and,

FIG. 16 is a right side view with antennas removed.

The broken lines are included for the purpose of illustrating portions of the wireless receiver that form no part of the claimed design.
